Quell, Warfield & Quell

ATTORNEY

UNITED STATES PATENT OFFICE.

WILLIAM J. PARSONS, OF MILLERS FALLS, MASSACHUSETTS, ASSIGNOR TO MILLERS FALLS COMPANY, OF MILLERS FALLS, MASSACHUSETTS, A CORPORATION OF MASSACHUSETTS.

HACK-SAW FRAME.

Application filed June 30, 1923. Serial No. 648,757.

- To all whom it may concern:*
- Be it known that I, WILLIAM J. PARSONS, a citizen of the United States, residing at Millers Falls, in the county of Franklin and 5 State of Massachusetts, have invented certain new and useful Improvements in Hack-Saw Frames, of which the following is a full, clear, and exact description, such as will enable others skilled in the art to which 10 it appertains to make and use the same.
- This invention relates to an improvement in tool frames and aims to provide a device of this character more particularly adapted for use in connection with saws and specifically 15 that type of device known as a hack-saw.
- It is an object of the present invention to provide an article of the character stated, which will embrace two major parts connected together, these parts each having 20 attached to them those subsidiary parts which may be necessary to provide a complete frame.
- It is a further object of the invention to 25 construct a frame of the nature aforementioned, which frame will be capable of being extended so that blades of different lengths may be accommodated within the same.
- A still further object of the invention resides 30 in the provision of a frame, the parts of which may be moved with respect to each other, but which parts are normally locked in such a manner that no movement 35 of the same can occur, this locking being accomplished by means of a simple expedient.
- Another object is to be predicated to the 40 provision of a tool frame involving a handle forming virtually an integral portion thereof.
- Other objects of the invention will in part be obvious and will in part appear hereinafter.
- The invention accordingly comprises the 45 features of construction, combinations of elements, and arrangement of parts, which will be exemplified in the constructions hereinafter set forth and the scope of the 50 application of which will be indicated in the claims.
- For a fuller understanding of the nature and objects of the invention reference should be had to the following detailed description
- taken in connection with the accompanying 55 drawing, in which:
- Fig. 1 is a side view with certain of the parts broken away to disclose the underlying structure, and
- Figs. 2 and 3 are transverse sectional 60 views taken along the lines 2—3 and 3—3, and in the directions of the arrows as indicated in Fig. 1.
- In these drawings it will be seen that the frame includes a **U** shaped body, embracing two major portions, one of the same comprising an **L** shaped body, consisting of a stem 5 and a lateral arm 6, while the second part includes a member presenting a stem 7 in the nature of a sheath and an arm 8 attached thereto in any desirable manner, such as, for example, by rivets. 65
- With a view of securing the stems 5 and 7 to each other, it will be noted that the former may carry a pin 9 adapted to engage selectively any one of a series of openings 10 formed in the base of the latter. Furthermore, it will be noted that the stem 7 of the second part is formed with offset portions 11 adjacent one of its ends and extending between these portions is a support 12 which is adapted to bear against the under edge of the stem 5 so that the latter is only capable of slidable, or swinging movement in one direction with respect 70 to the sheath 7, for a purpose hereinafter brought out.
- Fixedly attached to the sheath 7, adjacent its outer end, and at the junction of the arm 8 therewith, is an extension 13 which is disposed at an acute angle to this arm and at an obtuse angle to the sheath. A handle or grip suitable for manipulating the frame may be secured to this extension so 75 that it forms what virtually amounts to an integral portion thereof, by simple molding a suitable plastic material 14 around the extension 13, it being obvious that by this expedient the handle is rigid with the frame and that there is no danger of play coming 80 into existence between these parts.
- In order to secure a blade 15 to the frame, suitable attaching means may be associated with each of the arms 6 and 8 adjacent their outer ends, this attaching means in 85 the present instance embracing blade anchoring mechanism 16 carried by the arm 6 and a blade tensioning mechanism 17,

secured to the outer end of the arm 8, it being apparent that the greater the amount of tension to which the blade is subjected, the more firmly the parts of the frame will be locked with respect to each other.

In use it will be understood that the inner end of the stem 5 is introduced into the channel of the sheath provided by the stem 7, it being obvious that during this operation the two parts of the frame are angularly disposed with respect to each other. After these parts have been telescoped to such an extent that the arms 6 and 8 are spaced from each other a proper distance to accommodate therebetween the particular blade which is to be mounted by the frame, the stems 5 and 7 are swung until they align, i. e., to the position illustrated in Fig. 1, and the pin 9 is brought to extend into that opening 10 adjacent which it is disposed, so that any further longitudinal movement of the parts with respect to each other is avoided. One end of the blade 15 may now be attached to the anchoring mechanism 16 and the opposite end thereof is now associated with the tensioning mechanism 17, and the latter is manipulated to exert a drafting action on the blade. This pull will obviously be transmitted to the arm 6 and the latter, incident to its connection with the stem 5, will tend to cause this member to swing with respect to the stem 7, the support 12 acting as a pivot for this swinging action. Due to the fact, however, that the two major parts of the frame are incapable of such swinging movement, this action will result in the parts being firmly interlocked.

It is obvious in this connection, that due to the fact that the arm 6 is integral with the stem 5 while the arm 8 is virtually integral with the stem 7, that no movements can occur at these points and thus, although the frame is rendered adjustable by having its major portions capable of telescoping movement with respect to each other, the frame, when its parts are in locked position, permits of no movement of either of the arms relative to each other.

Also, it will be noted that the handle as aforesaid, is provided by having the same form what virtually amounts to an integral portion of the frame, this handle being reinforced and anchored in position by the angular member 13 which extends substantially the full length of the grip and projects into the channel of the stem 7, as in Fig. 2, and also for the reason that this handle is preferably extended to envelope the rear end of this stem and to be in intimate contact therewith, it being seen in fact, as in Fig. 2, that the material of the handle may key into the channel of the stem.

From the foregoing it will be appreciated

that by means of the present invention there is provided a frame which is of peculiar virtue when used in connection with a hack-saw blade, in that this frame, although being extensible, involves merely two major parts which are capable of movement with respect to each other, although the same are normally locked in such a positive manner that no movement can occur and that no play will come into existence. Furthermore, it will be understood that the handle herewith suggested, forms what is virtually an integral portion of the frame so that all difficulties in this connection are also avoided.

Thus, the objects of this invention are accomplished and it will be appreciated that since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent, is:

1. A hack-saw frame, including, in combination, a sheath U-shaped in cross section, an arm disposed substantially at right angles thereto and at a point short of the end thereof, said arm having its inner end projecting between the side walls thereof and rigidly secured thereto, a stem slidable within said sheath, an arm carried by said stem, blade-securing means associated with said last- and first-named arms, a handle member independent of said first-named arm, said member having a beveled end-portion and being arranged adjacent the end of said sheath with its beveled end resting against the base thereof whereby the body of said member extends obliquely thereof, and means for securing the handle member in such position.

2. As an article of manufacture, a tool frame including a sheath U-shaped in cross section, a handle member having a beveled end-portion extending into said sheath with its edge in contact with the base thereof whereby its body extends obliquely thereof, and a mass of plastic material enveloping said handle member and the point of connection of the same with said sheath, said material being keyed into the space extent between the side walls of said sheath.

In testimony whereof I affix my signature in the presence of two witnesses.

WILLIAM J. PARSONS.
